Primary Examiner—Doris Clark

(57) **CLAIM**

The ornamental design for a scaffold ledger, as shown and described.

DESCRIPTION

FIG. 1 is a left side elevational view of the scaffold ledger of the present design. The claimed design is broken on the left and right ends to indicate indefinite length in all of the Figures.

FIG. 2 is a top plan view of the scaffold ledger shown in FIG. 1.

FIG. 3 is a top left side perspective view of the scaffold ledger shown in FIG. 1; and,

FIG. 4 is a bottom right side perspective view of the scaffold ledger shown in FIG. 1.
